UNITED STATES PATENT OFFICE.

JOHN W. BROWN AND WILLIAM HESS, OF PHILADELPHIA, PENNSYLVANIA; SAID HESS
ASSIGNOR TO SAID BROWN.

SHEET-METAL-SEAMING MACHINE.

1,270,373.

Specification of Letters Patent. Patented June 25, 1918.

Application filed June 9, 1917. Serial No. 173,809.

To all whom it may concern:

Be it known that we, JOHN W. BROWN and WILLIAM HESS, citizens of the United States, residing at Philadelphia, in the 5 county of Philadelphia and State of Pennsylvania, have invented certain new and useful Improvements in Sheet-Metal-Seaming Machines; and we do hereby declare the following to be a full, clear, and exact description of the invention, such as will enable others skilled in the art to which it 10 pertains to make and use the same.

The present invention relates to that class 15 of machines adapted for handling sheet metal, and has more particular reference to a machine for trimming, edging, and seaming sheets of tin adapted to be subsequently rolled or otherwise conveniently packed for use in the construction of roofs, and the like.

20 The object is to provide a machine of this character adapted to perform these various operations automatically and consecutively; and wherein are employed relatively novel constructions and arrangements of the 25 parts whereby the number of parts are relatively few and are capable of being operated with the expenditure of but a relatively small amount of power.

20 The invention further aims at the provision of a machine of this type which is adapted to seam the meeting edges of sheet metal without the use of solder, and wherein interfitting beads of different sizes are formed upon the opposite edges of the sheet 35 metal and crimped to interlock the sheets together and seal the joint therebetween.

With these, and further objects in view, as will in part hereinafter become apparent and in part be stated, the invention comprises 40 certain novel constructions, combinations and arrangements of parts as subsequently specified and claimed.

In the accompanying drawings:

Figure 1 is a top plan view of a sheet 45 metal seaming machine constructed according to the present invention, parts being broken away.

Fig. 2 is an end elevation of the same, parts being broken away for the purpose of 50 clearness.

Fig. 3 is a fragmentary, enlarged view in longitudinal section taken through the edging mechanism at one side of the feed table.

Fig. 4 is an enlarged transverse section

taken through the edging apparatus substantially on the line 4—4 of Fig. 1.

Fig. 5 is a detail perspective view of one of the automatic clutch shifting devices employed.

Fig. 6 is a transverse section taken on the 60 plane indicated by the line 6—6 in Fig. 1, showing the seamer and presser employed.

Fig. 7 is a bottom plan view of the same.

Fig. 8 is a fragmentary elevation of a 65 pair of the trimming rollers arranged at one side of the feed table.

Fig. 9 is a transverse section taken through the interfitting edges of metal sheets subsequent to their passage through the edging and assembling mechanism. 70

Fig. 10 is a perspective view of adjacent sheets in their relative positions during assembly, and immediately subsequent to the crimping or edging of the adjacent sheet.

Fig. 11 is a detail perspective view of one 75 of the links of one of the feed chains, showing the detachable and adjustable sheet engaging finger employed.

Referring to the drawings, 15 designates a table adapted to receive sheets of metal 80 to be assembled, the table being provided near its outer end with a pair of coöperating feed rolls 16, adapted to receive the sheets of metal one at a time and advance the same into the machine. The table 15 is provided, 85 next adjacent to the feed rolls 16 with opposed pairs of trimming or cutting rolls 17, adapted to cut the sheets of metal into correct size and form, and prepare the sheets to be operated upon by the edging mechanism. 90 Between the edging mechanism and trimming rolls 17 are arranged a second set of feed rolls 18, the rolls 16, 17 and 18 being located at opposite sides of the table, and adapted to feed and cut the lateral edge 95 portions of the sheets, of tin, or other material to be operated upon, to true the edges of the sheets and conform the latter to the desired dimensions.

The edging mechanism is formed in two 100 sections of substantially similar construction and arranged at the opposite sides of the table 15. Each section embodies pairs of superposed rollers 19 and 20 which are mounted upon vertically spaced apart 105 shafts 21, and which are adapted to receive the sheets of tin between the rollers 19 and 20. Anvil plates 22 are arranged between

the lower rollers 19, and substantially fill the spaces between the rollers, the anvil plates 22 being arcuated at opposite ends to substantially conform to the adjacent side portions of the rollers 19. The anvil plates 22 are two in number at each side of the machine, and three pairs of rollers 19 and 20 are employed.

Overhanging the anvil plates 22 at each side of the table 15, is a former 23 comprising a plate having down-turned longitudinal flanges, the depths of which gradually increase from the outer or forward end of the former 23 to the rear end thereof as shown in full and in dotted lines in Fig. 3. The anvil, or anvil plates 22, at the outer or left hand side of the table 15, is relatively narrow in width as compared with the width of the anvil 22 at the inner or right hand side of the table, and the formers 23 are of correspondingly different sizes. The former plates 23 may be of greater length than the anvils 22, are slotted to receive the upper rollers 20 therethrough, and are adapted to be separated in closely spaced relation about the upper edges of the anvils 22. Longitudinally slotted ears 24 project laterally from the edging devices and are held to the table 15 in various adjusted positions, by clamping bolts having winged nuts 25.

The table 15 extends laterally from one end of a bed-plate 26, and the latter is adapted to receive, delivered transversely across said end, sheets of metal, or the like, being operated upon. The bed-plate 26 is provided, also at said end, with a pair of longitudinally extending endless conveyers 27, counter-sunk in the upper face of the bed-plate 26, and having a pair of adjustably mounted fingers 28 extending outwardly therefrom. As shown in Fig. 11, the fingers 28 may comprise yoke base portions 29 adjusted to straddle or fit over a link of each chain or conveyor 27, and being detachably held to the links by set screws 30. The fingers 28 are mounted on their respective conveyers 27 in transverse alinement, and are adapted to engage the inner end of a sheet of metal and carry the latter forwardly over the bed-plate 26 toward the opposite end of the latter.

It will be noted that the conveyers 27 are relatively short, and that they are of a length only equal to the width of the edging mechanism. Near the opposite or outer end of the bed-plate 26, and across the upper side of the same is mounted a feed screw or threaded shaft 31 journaled at opposite ends in posts 32 which rise from the bed-plate 26, and which has beveled gears 33 and 34 on opposite ends for driving the threaded shaft 31 in opposite directions. Mounted in screw threaded relation upon the shaft 31 is a combined seamer and presser, the same comprising a block 35 formed with a screw-threaded

opening therethrough receiving the shaft 31, having a pair of transversely spaced apart beveled rollers 36 mounted upon the lower face of the block with their axis of rotation in vertical planes, and having, in rearwardly spaced relation to the transverse axis of the rollers 36, an intermediate presser roller 37 seated in the lower face of the block 35 and being mounted upon a pivot, the axis of which extends horizontally and transversely in the block.

The table 15 and the bed-plate 26 are mounted upon any suitable framework structure, and in the present instance, legs or standards 38 are employed. A pair of 80 the standards 38 is arranged at the inner end of the bed-plate 26, and a driving shaft 39 is journaled across the said standards 38 and provided with a pulley 40 adapted to receive a belt or the like, thereover for 85 transmitting power of the shaft 39. The shaft 39 has, adjacent each standard 38, a gear wheel 41, and arranged above the shaft 39, and over the ends thereof is a pair of counter-shafts 42 and 43, journaled at their 90 inner ends in a common bearing 44, and being supported near their outer ends in bearing brackets 45 mounted upon the standards 38. The counter-shaft 42 has on its outer end a beveled gear wheel 46 meshing with a second beveled gear wheel 47 which is mounted upon a shaft 48 extending along one side of the bed-plate 26, and having, upon its opposite end, a second beveled gear wheel 49. The beveled gear wheel 49 meshes with a 100 correspondingly beveled gear wheel 50 carried upon the lower end of a vertically extending shaft 51 carried at one side of the frame of the machine, and which has on its upper end a beveled gear wheel 52 meshing 105 with the beveled gear wheel 33 of the screw-threaded shaft 31. Loose upon the counter-shaft 42 is a spur gear wheel 53, and the counter-shaft 42 is provided with a shiftable clutch element 54 adapted to interlock the 110 gear wheel 53 to the counter-shaft for driving the latter and the train of gears connected thereto from the driving shaft 39.

The counter-shaft 43 has a beveled gear wheel 55 near its outer end which meshes 115 with a beveled gear wheel 56 carried upon the adjacent end of a shaft 57 which extends longitudinally of the opposite side of the machine, and which is provided upon its rear or opposite end with a beveled gear 120 wheel 58 meshing with a beveled gear wheel 59 carried upon the lower end of a vertically extending shaft 60. The shaft 60 has on its upper end a beveled gear wheel which meshes with the beveled gear wheel 34 125 mounted upon the opposite end of the threaded shaft 31. The counter-shaft 43 is provided with a spur gear wheel 62 meshing with the gear wheel 42 of the driving shaft 39, and which is adapted to be inter- 130

locked with counter-shaft 43 by a shiftable clutch element 63. The train of gears connected to the counter-shafts 42 and 43, and connected to the opposite ends of the 5 threaded shaft 31, are adapted to drive the shaft 31 in opposite directions for reciprocating the combined seamer and presser across the bed-plate 26.

The counter-shaft 43 has upon its outer 10 end a sprocket wheel 64 over which is trained a chain 65, the latter passing over a sprocket wheel 66 mounted on a worm shaft 67 arranged longitudinally at one side of the table 15. The shaft 67 is provided 15 at suitably spaced apart points with worms 68 meshing with worm wheels 69 carried upon the shafts of the feed rolls, the cutting rolls, and the edging rolls for the purpose of driving the same.

20 When the counter-shaft 43 is driven by means of the spur gear wheels 41 and 62, the worm shaft 67 is actuated to advance the sheets of tin, or the like, through the trimming and edging mechanisms, and to deposit 25 the sheets, delivered from the edging mechanism, on the rear end of the bed-plate 26. At the same time, the counter-shaft 43 actuates its train of gears and drives the threaded shaft 31 in a direction to move the combined seamer and presser 35 across the outer 30 end of the bed-plate 26 for closing the seam of any connected sheets that may have been deposited beneath the block 35 by prior operations of the machine.

35 When the block 35 has traversed the bed-plate 26 in one direction, the counter-shaft 43 must be disconnected by the driving shaft to arrest the operation of the feeding, trimming, and edging mechanisms and 40 prevent the stacking or the piling up of sheets upon the inner end of the bed-plate. It is also necessary at this time to return the block 35 to the opposite side of the bed-plate, and to actuate the conveyers 27 for 45 advancing the adjacent pair of connected sheets for the purpose of interlocking the sheets and pressing the interlocking seams of the same.

To accomplish this result, the bed-plate 50 26 is provided at opposite sides with clutch shifting devices which have connection with the clutch elements 54 and 63 at one end, and which include rocker arms 70 and 71 projecting toward the shaft 31 and located 55 at the opposite sides of the bed-plate 26. The arms 70 and 71 are mounted upon vertical shafts 72 which project upwardly through the lateral portions of the bed-plate 26, and support the arms in the path of a 60 shifting finger 73 projecting rearwardly from the block 35.

The shafts 72 have outwardly extending arms 74 upon their lower ends to which are pivotally connected rods 75, the rear ends 65 of which are pivotally connected to posts 76

which rise from the outer ends of bell-crank levers 77 pivotally mounted at their inner portions upon pins 78 carried at the opposite sides of the frame. The bell-crank levers 77 are arranged adjacent to the clutch elements 70 54 and 63, and have rearwardly extending arms which are forked, and which are connected to the elements 54 and 63 for shifting the same upon the rocking of the bell-crank levers 77. The counter-shaft 42 is provided 75 with a sprocket wheel 79 carrying a chain 80 which passes over a second sprocket wheel 81 mounted upon a transversely extending conveyer shaft 82 for turning the latter when the counter-shaft 42 is actuated. 80 The shaft 82 is provided with sprocket wheels 83 suitably spaced apart and over which the conveyers 27 are trained, the forward ends of the conveyers passing over suitably mounted sprocket wheels 84. 85

It is essential that the clutch elements 54 and 63 be alternately engaged and disengaged with their respective gear wheels 53 and 62, and for this purpose the bell-crank levers 77 are provided, upon their outwardly 90 extending arms, with lugs 85 to which are pivotally connected the opposite ends of a tie-rod 86 for communicating the motion of one bell-crank lever to the opposite bell-crank lever and, the clutch elements being 95 arranged upon the opposite outer sides of the spur gear wheels 53 and 62, alternately couple and release the counter-shafts 42 and 43 to and from the driving shafts 39.

In operation, a sheet of tin, or the like, 100 A is placed upon the table 15 and is introduced between the rollers 16, which latter carry the sheet A into the trimming rollers 17. The trimming rollers 17 correct any defects in configuration of the end edges of the 105 sheet A, and the sheet emerges from the trimming rollers 17 into the second set of feed rollers 18, and is thence delivered therefrom to the edging mechanism.

As clearly shown in Fig. 1, the edging 110 mechanism at the left hand side of the table 15 is relatively narrow as compared with the opposite side, and when the plate A emerges from the edging mechanism, it is provided upon its rear end with a relatively 115 small upstanding bead or crimped portion B and a relatively large bead or crimped portion C upon its forward end.

The edging mechanism delivers the sheet A on the conveyers 27, and the fingers 28 of 120 the latter engage the rear end of the sheet A and carry the same a distance of advance equal to the distance between the center lines of the edging dies. When the sheet A is thus advanced, the small bead B thereof is 125 brought into longitudinal alinement with the larger section of the edging mechanism.

In a like manner, a second sheet D passes 130 over the table 15 to the bed-plate 26, and as the sheet D emerges from the edging mech-

anism, the large bead C slides over the small bead B of the first plate A, forming an overlapping joint as shown in Fig. 9.

Operation of the conveyers 27 now advances the sheets A and B into a position to dispose the small bead B of the plate D in register to receive the large bead of a succeeding plate or sheet thereover. The seaming and pressing device is spaced forwardly 10 from the conveyers 27 a distance equal to the distance of advance of the conveyer fingers 28 so that as the small bead B of the rear-most sheet or plate is held in position to receive a succeeding enlarged bead C there-over, the overlapping beaded edges of two adjacent plates are held in alinement beneath the block 35.

When the sheet A travels over the table 15 the mechanism is so connected to the counter-shaft 43, that the block is simultaneously driven in such direction as to press and close the seam of the overlapping plates. The arm 73 strikes the rocker arm 70 when the seam is sealed and reverses the clutches 54 and 63 25 whereupon the feeding mechanism on the table 15 is arrested and the counter-shaft 42 is set in motion to actuate the conveyers 27 for advancing the sheets forwardly over the bed-plate 26, and for returning the block 35 30 to its initial position. The rocker arm 70 is tripped only after the block 35 has completed its transverse movement across the overlapping ends of the sheets and has moved beyond the adjacent lateral edges 35 thereof. The tripping of the arm 70 sets the feeding mechanism in motion and the same is advanced sufficiently during the initial return movement of the block 35 to clear the seam formed and admit the free advancing 40 of the sheets and the free return movement of the block. As soon as the block 35 returns to its initial position, the arm 73 thereof strikes the rocker arm 71 and reverses the positions of the clutches 54 and 63, resulting 45 in releasing the shaft 42 from the driving shaft and connecting the shaft 43 thereto.

The operation of the machine is therefore continuous and automatic and may be carried on until the source of power is shut off.

50 It is of course, understood that various changes in the structure and design in parts may be made without departing from the spirit of the invention, to meet various conditions met with in the installation of the 55 machine and to accommodate the same to various material and sizes of sheets to be worked upon.

What is claimed is:

1. In a sheet metal seaming machine, the 60 combination of a bed plate, means for delivering sheets of metal on the bed plate and including edging devices for the sheets, means for advancing the sheets over the bed plate a distance less than the distance between the formed edges of the sheets, a com-

bined seamer and presser arranged to move transversely across the bed plate at a second like advanced distance from said advancing means, means for simultaneously advancing the sheets over the bed plate and moving the 70 seamer and presser into an initial position for use, and other means for simultaneously actuating the delivery means to overlap succeeding sheets on the bed plate and to actuate the seamer and presser for crushing the 75 advanced overlapping sheet ends together.

2. In a sheet metal seaming machine, the combination of a bed plate, edging mechanism arranged at one side and at the inner end of the bed plate adapted to intermittently deliver sheets of metal laterally upon the bed plate with crimped opposite ends, means on the bed plate operable when the edging mechanism is at rest to advance the sheets intermittently a distance equal substantially to the distance between the center lines of the two crimped ends to dispose the rear edge of an advanced sheet in line to receive the front edge of the next succeeding sheet, a transversely operable seamer arranged over the bed plate in position to press together the overlapping edges of adjacent sheets, and connections between the seamer and the edging mechanism and the advancing means to move the presser over overlapped advanced ends of sheets during the operation of the edging mechanism and to return the seamer to initial position during the advancing of the sheets.

3. In a sheet metal seaming machine, the combination of a bed-plate, edging mechanism arranged at one side and at one end of the bed-plate, operating means including a clutch element for actuating said edging mechanism, a conveyer arranged on the bed-plate for advancing sheets there-over delivered from the edging mechanism, a second operating mechanism including a clutch element for actuating said conveyer, a seaming device arranged to traverse the bed-plate and having connection with said operating mechanisms, and clutch shifting devices arranged at the opposite sides of the bed-plate for engagement with said seaming device at the ends of its transverse movements for alternately actuating said clutches and intermittently feeding sheets over the edging mechanism to the bed-plate and for intermittently advancing the sheets over the bed-plate to the seaming device.

4. In a sheet metal seaming machine, the combination of a bed-plate, a feed table arranged at one side of the bed-plate, feed rolls arranged on the feed table and adapted to advance sheets of metal thereover, 125 edging devices at the opposite sides of the table for operation upon the sheets to crimp the ends thereof, a conveyer arranged upon the bed-plate adapted to receive sheets delivered from the edging de- 130

vices, a seaming device traversing the outer end of the bed-plate, operating means connected to said feed rolls and said edging devices and including a clutch element, a 5 second operating means connected to said conveyer and including a clutch element, both of said operating means having connection with said seaming device and being controlled by said clutches for intermittently actuating the feeding and edging elements and the conveyer and for operating the seaming device in opposite directions.

5. In a sheet metal seaming machine, the 15 combination of a bed-plate, feeding and edging devices arranged at one side of the bed-plate adapted to crimp sheets of metal with beads of different sizes on opposite ends and deliver the same transversely to the bed-plate, advancing means upon the bed-plate adapted to advance the sheets to bring the small beads thereof into register with the larger beads of the next succeeding sheets, means for seaming the overlapping 25 beads, a driving element, alternately operable connecting means between the driving element and said feeding and edging means and said seaming device for simultaneously actuating the same and driving the seaming device in one direction, and adapted to actuate said advancing means and to drive said seaming device in 30

an opposite direction, and controlling elements associated with said connecting means and operable by said seaming device 35 at the ends of its transverse movements.

6. In a sheet metal seaming machine, the combination of a bed plate, feeding means for moving sheets one at a time laterally upon one end of the bed plate, beading 40 means for crimping beads across the opposite ends of the sheets simultaneously with the feeding of the sheets, advancing means for intermittently moving the sheets along the bed plate a distance sufficient to bring 45 the bead on the inner end of a sheet on the bed plate in line with the bead on the forward end of a sheet in the feeding means, the beading means being adapted to form 50 the beads in the inner end of the sheets of less size than that of the beads on the forward ends of the sheets for interlocking the beads of adjacent sheets by the feeding of 55 the succeeding sheets upon the bed plate, and seaming means for pressing the interlocked beads together.

In testimony whereof we affix our signatures in presence of two witnesses.
